UNITED STATES PATENT OFFICE.

JOSEF MICKL, OF NOVI-SAD, YUGOSLAVIA, ASSIGNOR OF THREE-SIXTHS TO ROBERT ALT & CO., ONE-SIXTH TO FRANZ MANNSBARTH, AND ONE-SIXTH TO JOSEF LABUT, ALL OF VIENNA, AUSTRIA.

RESILIENT SUPPORT OR BASE FOR CHAIRS, FAUTEUILS, BENCHES, TYPEWRITING MACHINES, AND THE LIKE.

Application filed July 31, 1925, Serial No. 47,235, and in Austria February 12, 1925.

This invention relates to improvements in resilient supports or bases for chairs, fauteuils, benches, the feet of typewriting machines, and the like, by which a non-yielding 5 or not sufficiently resilient chair for instance can be transformed, in a most simple manner, into a soft and comfortable seat.

The arrangement according to the present invention possesses the great advantage, that 10 it can be quickly and easily attached to or detached from the leg of a chair or the like quite independent of the shape or cross-sectional area of the leg.

One mode of carrying out the present invention is shown, by way of example, in 15 part-sectional elevation on the accompanying drawing.

The support or base consists of two hollow cylindrical members 1 and 2, each partially closed at one end and slidably mounted 20 within each other. In the illustrated embodiment the said members are prevented from becoming disconnected by turning-in the open end of the member 1 and flaring 25 out the open end of the other member.

A compression spring 3 is enclosed in the casing formed by the two members 1 and 2, and the ends of this spring bear against the ends of said members. Thus the spring has 30 the tendency to retain the two members in the outermost position.

The end of the member 1 is provided with an opening 4 for the passage of a screw, in order to fix the support to the leg of a chair

or the like. The end of the member 2 is furnished with an opening 5 for introducing the screw above mentioned and for applying a screw-driver to the latter. The rims encircling the said openings are turned inward to form a good seat for the ends of 40 the spring 3.

By a construction of this character it will be possible for the member 1 not only to have a vertical movement relative to the member 2, but also a slight lateral movement 45 or rocking action with respect thereto.

I claim:

A resilient support of the class described, including upper and lower hollow members having adjacent open ends telescoping one 50 within the other, the inner end being outward and the outer end being turned to abut said outward end to prevent detachment of one member from the other, the upper end of said upper member having a 55 closed end provided with an opening for the reception of a fastening means for attaching the support to a chair leg or the like and the lower closed end of said lower member also having an opening through which said 60 fastening means may be introduced into the first named opening, and a spring interposed between the closed ends of said upper and lower members and permitting vertical and lateral movements of the upper member relative to the lower member.

In testimony whereof I affix my signature.

JOSEF MICKL.
